AUTOMOBILE RUNNING BOARD LAMP

Filed Feb. 5, 1930

UNITED STATES PATENT OFFICE

WILLIAM A. GULLETTE, OF WHEELING, WEST VIRGINIA, ASSIGNOR OF TWO-THIRDS TO S. K. FRANK, OF WHEELING, WEST VIRGINIA, AND ONE-THIRD TO CHAS. A. DICK, OF WHEELING, WEST VIRGINIA, AS TRUSTEE FOR JOHN E. STEVENSON, VAL G. GUNDLING, AND CHAS. A. DICK

AUTOMOBILE RUNNING-BOARD LAMP

Application filed February 5, 1930. Serial No. 426,062.

This invention relates broadly to running-board lamps for automobiles, and more specifically to a support or bracket for such lamps.

5 The primary object of the invention is to provide a simple, strong and comparatively inexpensive supporting bracket for the running-board lamps of automobiles, which is adapted to be adjusted to dispose the lamp either in its operative position or in an out-of-the-way position, and also provided with means whereby said lamp is maintained steadily in its adjusted position.

A further object is to provide a simple 15 means of attachment between the lamp and said bracket, said means permitting adjustment of said lamp with respect to the bracket as may be required.

A still further object is to structurally improve and simplify the structure disclosed in my prior Patent No. 1,675,931, granted July 3, 1928.

In describing the invention in detail, reference is herein had to the accompanying 25 drawings, in which—

Figure 1 is a top plan view of the invention, showing it mounted on an automobile running board and occupying its operative position;

30 Figure 2 is a front elevation of the same, the running board being shown in section;

Figure 3 is a section taken on line 3—3, Fig. 1;

Figure 4 is a fragmentary top plan view of 35 the bracket, parts being shown broken away;

Figure 5 is a section on line 5—5, Fig. 2; and—

Figure 6 is a detail section showing a modification.

40 Referring to said drawings, 1 designates a hollow cylindrical casing or pedestal, preferably made of sheet metal, having a closed upper end 2 and an open lower end, an annular flange 3 being formed on said lower 45 end through which attachment with the running board 4 is made, as by means of bolts 5.

Disposed for rotary movement on the upper end 2 of said casing 1 is a sheet metal cap-plate 6 which, preferably, has a downwardly turned annular flange 7 disposed in non-bind-

ing relation to said casing, as shown in Fig. 3. Attached to the pedestal by means of a vertically disposed hollow or tubular bolt 8 which is directed centrally through its upper end and through the overlying cap-plate 6 is a bracket arm 9 upon the end of which is mounted a lamp casing 10, said arm being adapted for rotary movement together with said cap-plate for positioning the lamp casing, as will hereinafter be explained.

The bracket arm 9 has an upwardly dished head portion 9^a of approximately circular form, providing a vertically disposed flange 9^b which occupies frictionally seated relation to the cap-plate 6. The bolt 8, which occupies vertical centrally disposed relation to said cap-plate and the upper end 2 of the pedestal, as hereinbefore stated, may either have an integral head on its lower end (not shown) or may have threaded on said end 60 a nut 11, as shown in Fig. 3.

Interposed between said head, or said nut 11, as the case may be, and the under face of the end 2 of the pedestal 1 is a bolt-encircling spiral spring 12. Also, said bolt has its upper end threaded, and mounted on said end is a nut 13 adapted to be adjusted for placing said spring 12 under greater or less tension to increase or decrease the pressure applied to the cap-plate 6 through the arm 9 for regulating the frictional resistance to rotary movement offered between said cap plate and said pedestal 1. As is obvious, adjustment of the nut 11, where such is employed, will effect the same result; however, because at 70 all times readily accessible, it is preferred that the nut 13 be utilized for effecting the required adjustment.

The outer end 9^c of the arm 9 is made of tubular form, and, as herein shown, has disposed in embracing relation thereto a split ferrule 14 which projects outwardly from the lamp casing 10. Said ferrule is adapted to be compressed into tightly gripping relation to said tubular end 9^c by means of a clamp 15 of open ring form having parallel terminal lugs 16 adapted to be attached by a bolt 17. Manifestly, this construction permits the lamp to be adjusted by rotation on the bracket arm as required to elevate or lower 95 100

the projected light beams emanating from the lamp.

A spring pressed contact pin 18 projecting inwardly of the lamp casing and into engagement with a current-conducting contact piece 30 carried by said casing is mounted within the tubular end 9^a of the bracket arm 9 and has suitably attached thereto the bared end of an insulated electrical current conducting wire or cable 19 which leads from a source of electric current, as the storage battery 20 of the automobile. Said cable leads into the lower part of the bracket pedestal, as through a hole 22 provided therefor in the running board 4, and thence is directed upward through the interior of the bolt 8 to, and is thence directed outward through, a hole 21 provided therefor in the side of the body of said bolt and located at a point between the top of the arm 9 and the cap-plate 6, whence it leads horizontally to said contact pin 18.

In practice, the bracket pedestal is rigidly mounted in an appropriate position upon the running board, the cap-plate 6 and bracket arm 9 having previously been assembled through the intermediacy of the tubular bolt 8. The nut 13 is then adjusted to place the spring 12 under proper tension, following which the bracket arm 9 may be swung for disposing the lamp either in its operative position wherein it projects outwardly with respect to the outer edge of the running board, as shown in Figs. 1, 2 and 3, or in one or the other of its inoperative, or out-of-the-way positions wherein it overlies the running board either forward or rearward of the pedestal, the last mentioned position being indicated in dotted lines in Fig. 1.

The upper end 2 of the pedestal 1 has formed in its upper face a plurality of small upwardly pressed or indented knobs or buttons 23 of substantially semi-spherical form, said buttons being preferably four in number and being located in regularly spaced relation at equi-distant points from the axis of the pedestal. Also formed in the under face of the overlying cap-plate 6 and adapted to occupy registering relation to said buttons is a plurality of upwardly pressed buttons 24 providing on their under sides indented seats adapted to receive the buttons 23 therein, said seats corresponding in form and size to said buttons 23. Said buttons and seats are designed to coact for maintaining the cap-plate against chance rotary movement with respect to the pedestal following movement of the bracket arm to any adjusted position.

It is to be understood that when the spring 12 has been placed under proper tension, effected as hereinbefore described, the flange 9^b of the arm 9 is so firmly seated upon the cap-plate that rotary or swinging movement imparted to the former produces a corresponding movement of the latter. That is

to say, due to the frictional binding relation which exists between the arm and the cap-plate, said parts move as one in the positioning of the arm. In rotating from one seated position to another, actuated by force applied to the lamp casing 10 and communicated thereto through the arm 9, the cap-plate, as it starts to rotate, is caused to elevate slightly against the tension of the spring 12 to effect unseating of the buttons 23 relative to the seats 24 and then remains elevated to the end of the rotating movement where the buttons re-enter the seats 24 provided therefor.

Obviously, the modification disclosed in Fig. 6 in which upwardly facing seats 25 are provided in the end 2^a of the pedestal 1^a may be employed, said seats being adapted to register with the seats 24 of the cap plate, and balls 26 being normally disposed in seated relation to both sets of seats.

A suitable stop, as the head of a screw 27 mounted in the cap plate at an appropriate point, is located beneath the bracket arm 9 and is adapted to be engaged by the flange 9^b of said arm at one side or the other for limiting the extent of rotary movement of the latter with respect to the cap-plate, as when it is desired to slightly adjust said arm forward or back with respect to said cap-plate prior to setting up the adjusting nut 13 so that the lamp will be more accurately focused in the desired direction when the operative position of the bracket is assumed.

What is claimed is—

1. A support of the character mentioned comprising a hollow pedestal adapted for mounting on the running board of an automobile, said pedestal having an upper closed end, a rotary cap plate overlying said closed end, a bracket arm surmounting and normally rotatable with said cap plate, adjustable tension means securing said cap plate and said arm in axial relation to said pedestal, and interengageable means between said cap plate and said pedestal whereby the former is held in any of a plurality of positions against chance rotary movement.

2. A support for the running board lamps of automobiles, comprising a hollow pedestal adapted to be rigidly mounted on the running board, said pedestal having an upper closed end, a cap plate mounted for rotary movement on said closed end, a lamp carrying arm overlying said cap-plate and normally immovable with respect to the latter, a pivot-bolt connecting said cap plate and said arm to said pedestal, a compression spring associated with said bolt whereby said cap-plate is maintained seated under yielding tension, and means providing for interengagement between said cap plate and said pedestal whereby the former is held against chance rotary movement from any of a plurality of positions.

3. A support for the running board lamps of automobiles, comprising a hollow pedestal adapted to be rigidly mounted on the running board, said pedestal having an upper closed end, a cap plate mounted for rotary movement on said closed end, a lamp carrying arm overlying said cap-plate and normally immovable with respect to the latter, a vertically disposed bolt securing said cap plate and said arm in axially pivoted relation to said pedestal, said bolt having its upper end threaded and projecting above said arm, resilient means normally tending to hold said bolt in a lowered position, a nut carried by said projecting end of said bolt whereby the tension of said resilient means is adjusted for regulating the frictional resistance to rotary movement of said cap plate, and means providing for interengagement between said cap plate and said pedestal whereby the former is held against chance rotary movement from any of a plurality of positions.

4. A support for the running board lamps of automobiles, comprising a hollow pedestal adapted to be rigidly mounted on the running board, said pedestal having an upper closed end, a lamp carrying arm overlying said cap-plate and normally immovable with respect to the latter, a vertically disposed tubular bolt securing said cap plate and said arm in axially pivoted relation to said pedestal, said bolt having its upper end threaded and protruding upwardly through said arm and also having its lower end depending below said closed end of the pedestal, a compression spring encircling the lower end portion of said bolt and tending to maintain the latter yieldingly in downwardly drawn position, a nut carried by the protruding upper end of said bolt whereby the tension of said spring may be adjusted for regulating the frictional resistance to rotary movement of said cap plate with respect to the pedestal, and spaced means borne by said cap plate and said closed end of the pedestal whereby the former is normally held in any of a plurality of relatively spaced positions against chance rotary movement.

5. A support for the running board lamps of automobiles, comprising a hollow pedestal adapted to be rigidly mounted on the running board, said pedestal having an upper closed end, a cap plate mounted for rotary movement on said closed end, a lamp carrying arm overlying said cap-plate and normally immovable with respect to the latter, a vertically disposed tubular bolt securing said cap plate and said arm in axially pivoted relation to said pedestal, said bolt having its upper end threaded and protruding upwardly through said arm and also having its lower end depending below said closed end of the pedestal, a compression spring encircling the lower end portion of

said bolt and tending to maintain the latter yieldingly in downwardly drawn position, a nut carried by the protruding upper end of said bolt whereby the tension of said spring may be adjusted for regulating the frictional resistance to rotary movement of said cap plate with respect to the pedestal, spaced means borne by said cap plate and said closed end of the pedestal whereby the former is normally held in any of a plurality of relatively spaced positions against chance rotary movement, said bolt having a hole in the side thereof intermediate said arm and said cap plate, and a current conducting cable leading upward through the interior of said bolt, outward through said hole and thence to the lamp.

In testimony whereof I affix my signature.
WILLIAM A. GULLETTE.
